UNITED STATES PATENT OFFICE

FLOYD S. YOUNG, OF SHENANDOAH, IOWA, ASSIGNOR TO MAY SEED & NURSERY CO., OF SHENANDOAH, IOWA, A CORPORATION OF IOWA

DESIGN FOR A TIRE OR SIMILAR ARTICLE

Application filed July 2, 1928. Serial No. 27,359. Term of patent 3½ years.

To all whom it may concern:

Be it known that I, FLOYD S. YOUNG, a citizen of the United States, and residing in the city of Shenandoah, in the county of Page and State of Iowa, have invented a new, original, and ornamental Design for a Tire or Similar Article, of which the following is the specification, reference being had to the accompanying drawings, forming a part thereof.

On the drawings:

Figure 1 is a fragmentary plan view of the tire illustrating clearly my novel tire tread.

Figure 2 is a fragmentary transverse section of the tire shown in Figure 1.

I claim:

The ornamental design for a tire or similar article, as shown.

FLOYD S. YOUNG.
